Patented Dec. 21, 1926.

UNITED STATES PATENT OFFICE.

HARRY NAGIN, OF BROOKLYN, NEW YORK, ASSIGNOR TO THE GRATING COMPANY OF AMERICA, OF PITTSBURGH, PENNSYLVANIA, A CORPORATION OF PENNSYLVANIA.

CONNECTED-BAR STRUCTURE.

Application filed July 25, 1925. Serial No. 45,984.

My invention relates to a new and improved connected bar structure.

One of the objects of my invention is to provide a structure consisting of a series of longitudinal bars and a series of cross bars, in which the cross bars are connected to the longitudinal bars in a simple, reliable and efficient manner.

Another object of my invention consists in making a connected bar structure of this type which is useful for gratings in sidewalks or at other points, for protecting windows and for other purposes, in which the cross bars are very firmly and reliably connected to the longitudinal bars without the necessity of using rivets or expanding or enlarging the ends of the cross bars.

Other objects of my invention will be set forth in the following description and drawings which illustrate a preferred embodiment thereof, it being understood that the above general statement of the objects of my invention is intended to generally illustrate the same and not to limit it in any manner.

Figure 1 is a section on the line 1—1 of Figure 2.

Figure 2 is a top view illustrating one embodiment of my invention.

Figure 3 illustrates another embodiment of my invention.

Figure 4 is a section on the line 4—4 of Figure 3.

Figure 5 is a perspective view showing one of the cross bars used in connection with the embodiment shown in Figure 3.

Figure 6 illustrates another embodiment of my invention.

In order to make the embodiment shown in Figures 1 and 2, the longitudinal bars 10 which are made of any suitable metal are provided with slots 13 having what may be called vertical portions and also having inclined branches. By a vertical slot is meant one which is perpendicular to the longitudinal edge of the respective bar 10 as my invention is not dependent upon any particular position of the longitudinal bars 10.

After the longitudinal bars 10 have been placed in proper relationship, the cross bars 11 which conform to the shapes of the vertical portions or branches of the slots 13 are forced into the slots or recesses 13 with great pressure. This pressure may be produced

by a hydraulic press or by any other suitable means. This pressure causes the bottoms of the cross bars 11 to enter into and assume the configuration of the inclined inner branches of the slots or recesses 13.

Hence, by this method of manufacture, the cross bars 11 are very firmly and reliably connected to the longitudinal bars 10 without the use of any rivets or other fastening devices and without the necessity of expanding or enlarging the inner ends of the said cross bars.

In the embodiment shown in Figures 1 and 2, the cross bars 11 are unslotted. In the embodiment shown in Figures 3, 4 and 5, the cross bars 11^a are provided with slots or recesses 12^a which may have any desired depth and the longitudinal bars 10 are provided with slots 13^a having the same configuration as that previously described.

In this embodiment and as illustrated in Figure 4, the cross bars 11^a are provided with tongues 13' which are separated from the main bodies of the respective cross bars 11^a by means of cuts or slits, so that the said tongues 13' can be bent to enter the inclined branches of the slots in the bars 10. In Fig. 5, the tongues 13' are illustrated as being bent outwardly, to show them clearly. However, when said tongues 13' are initially formed, they remain parallel to the body portions of the cross-bars 11^a. When the longitudinal bars 10 and the cross-bars 11^a are assembled, said bars are caused to engage by means of the vertical portions of the slots 13^a, and the slots 12^a, and then, when sufficient pressure is applied, the tongues 13' are caused to enter the inclined portions of slots 13^a. In order to clearly illustrate this construction, the tongue 13' associated with the left-hand bar 11^a in Fig. 3 has been omitted, but this construction is clearly shown in connection with the right-hand bar 11^a in said Fig. 3. When the longitudinal bars 10 have been interlocked with the cross-bars 11^a, the tops of the said longitudinal bars are flush with the tops of said cross-bars, as shown in Fig. 4. In the embodiment shown in Figure 6, the structure

resembles that previously illustrated in Figure 1, save that the inclined portions of the slots 16 in the longitudinal bars 10 are alternately inclined in opposite directions so that the ends of the cross bars 13 assume the configuration shown in Figure 6.

For example, while I have shown the outer ends of the slots as perpendicular to the longitudinal edges of the longitudinal bars, it would not be departing from my invention in any manner to incline the said outer ends of the slots to said edges at any desired angle. Similarly, if desired, the slots in the longitudinal bars could be formed or arranged with respect to each other so that 10 the cross bars could be connected to the longitudinal bars at any desired angle.

Thus, if in the device shown in Figure 2, the slots corresponding to one of the cross bars would be arranged on a line inclined (but 15 not perpendicular) to the said cross bars, then a suitable and sufficiently thin cross bar could be located in said slots, the said cross bar contacting with the edges of said slots.

In addition, the inclined inner ends of the 20 slots could have any desired shape or curvature and could be composed of several portions relatively inclined to each other. Of course, as a matter of manufacturing convenience it is desirable to use ordinary flat strips 25 of rolled material and to force these into a crooked slot. In the illustrated form of the invention, the slot is crooked at the bottom thereof, it consisting of an upper straight portion and a bottom curved portion.

30 I have shown a preferred embodiment of my invention but it is clear that numerous changes and omissions may be made without departing from its spirit.

I claim:—

35 1. A connected bar structure comprising a plurality of girder bars, the longitudinal edges of which are provided with crooked recesses of substantially constant width, and a cross bar having portions located in said 40 recesses, said portions being bent to substantially the same configuration as the recesses,

the portions of the cross bars intermediate the recesses being integral with the portions located in the recesses for substantially the entire depth of the last-mentioned portions. 45

2. As a new article of manufacture, a structure comprising a plurality of girder portions having crooked recesses formed in the longitudinal edges thereof and a cross bar fitting into the recesses, the portions of the cross bar which are engaged by said recesses being integral with the intermediate portions of said cross bar for substantially their entire depth and being permanently deformed to fit the recesses. 50

3. As a new article of manufacture, a structure comprising a plurality of girder bars having crooked recesses formed in the longitudinal edges thereof, and a cross bar having portions fitting into said recesses, the portions of the cross bar intermediate the recesses being generally flat, the portions lying in the recesses being integral with said intermediate portions for substantially their entire depth but being crooked to co-operate with the slots and hold the cross bar in place. 55

4. As a new article of manufacture, a connected bar structure comprising a plurality of girder bars, each having a crooked slot of substantially constant width therein, and a cross bar fitting into the slots, the portions of the cross bar lying between the slots being substantially flat, and the portions lying in the slots being deformed to correspond with the slots and hold the cross bar in place, the portions lying in the slots being integral with the intermediate portions for substantially their entire depth. 70

In testimony whereof I affix my signature.

HARRY NAGIN.
